ASSIGNORS TO THE GOSS PRINTING PRESS COMPANY, OF CHICAGO, ILLINOIS, A COR-
PORATION OF ILLINOIS.

WEB-ROLL MECHANISM FOR PRINTING-PRESSES.

1,301,125.

Specification of Letters Patent. Patented Apr. 23, 1919.

Application filed November 15, 1916. Serial No. 181,550.

To all whom it may concern:

Be it known that we, SAMUEL G. Goss, a citizen of the United States, and a resident of Glencoe, in the county of Cook and State of Illinois, and ERNEST JAMES SMITH, a subject of the King of England, and a resident of Chicago, in the county of Cook and State of Illinois, have invented certain new and useful Improvements in Web-Roll Mechanisms for Printing-Presses, of which the following is a specification, reference being had to the accompanying drawings.

Our invention relates to web roll mechanisms for printing presses or other web machines, and it has for its principal object the provision of new and improved means for changing from one web roll to another without stopping the press and preferably without slowing down the speed of operation. Our improved construction is of the general type set forth in the application of Samuel G. Goss, Serial No. 181,159, and we do not desire to claim by our application the subject-matter shown, described and claimed by the said prior application. Our invention comprises a frame adapted to support two rolls of paper, endless tape belts by which the web from either of said rolls is led to the press, means for setting a fresh roll into rotation in either position at substantially the same speed as that of the web running to the press from the other roll, and means for carrying the web from the fresh roll into contact with the web running from the other roll as the former web unwinds upon the rotation of the fresh roll. It is one of the especial objects of our invention to provide new and improved means for carrying the end of the web of the fresh roll into contact with the running web. It is another object of our invention to improve mechanisms of this type in sundry details hereinafter pointed out. The preferred means by which we have accomplished our several objects are illustrated in the drawings and are hereinafter specifically described. That which we believe to be new and desire to cover by this application is set forth in the claims.

50 In the drawings,

Figure 1 is a side view of a construction embodying our improvements;

Fig. 2 is a view of the construction illustrated in Fig. 1 as seen from the right in

said figure, the upper roll being removed 55 and the web from the lower roll being broken away to better show the remaining parts;

Fig. 3 is a fragmentary view taken substantially at line 3—3 of Fig. 1 at the far 60 side of the mechanism as shown in said Fig. 1;

Fig. 4 is a fragmentary view taken substantially at line 4—4 of Fig. 1 also at the far side of the mechanism shown in said 65 Fig. 1.

Referring to the several figures of the drawings, in which corresponding parts are indicated by the same reference characters,— 70 10 indicates a frame located in a compartment or room below that in which a printing press or other web machine is located. Web rolls 11—12 are supported by spindles 13—14, respectively, mounted in suitable bearings 15—16 supported in suitable position upon horizontally-extending arms 17—18, respectively. The web 19 from the web roll 12 in use, as shown in Fig. 1, extends upward from the roll and over a roller 20 which is revolvably mounted upon a shaft 21 75 which in turn is yieldingly mounted upon the frame 10. The web extends from the roller 20 between two rollers 22—23 which are mounted by means of shafts 24—25, respectively, upon the frame 10 in close 80 proximity to each other, being adapted to feed a web or webs forward between them. The web extends to the left from the rollers 22—23 between endless tape belts 26—27 which are mounted in suitable grooves in 85 the rollers 22—23, being supported in addition by means of sheaves or pulleys 28 upon shafts 29, 30 and 31. The upper end portions of the endless tape belts 26—27 are 90 not shown, but it will be understood that such belts are to be driven by any suitable arrangement of supporting and driving means upon the press or other web machine with which the web 19 is to be used, the belts 26—27 being driven at the same surface 100 speed as that of the web. The shafts 29 and 30 are also provided with roller sections 32 between the sheaves 28 for holding the web in proper smooth condition. A shaft 33 is yieldingly mounted upon the frame 10 immediately above the shaft 21, supporting in 105 position a roller 34 about which the web from the roll in the upper position is adapt-

ed to pass and from which such web extends to the rollers 22-23.

The rollers 20 and 34 are formed in sections to permit of sheaves or pulleys 35 being mounted upon the shafts 21-33, as is best shown in Figs. 2 and 3. The rollers 22 and 23 are also formed in sections to permit of sheaves or pulleys 36 being mounted upon the shafts 24-25 in alinement with the 10 sheaves or pulleys 35. Transversely-extending shafts 37-38 are provided with sheaves or pulleys 39-40, respectively, in alinement with the sheaves or pulleys 35-36. Tapes 41 secured to the sheaves or pulleys 39 extend 15 under the sheaves or pulleys 36, from thence about the sheaves or pulleys 35, and from thence to the sheaves or pulleys 40 to which they are secured, the tapes 41 being adapted to be reciprocated between the sheaves 39 and 20 40 by being wound alternately upon one or the other set of such sheaves. Transversely-extending shafts 42-43 are likewise provided with sheaves or pulleys 44-45, respectively, in alinement with the sheaves 35-36 25 upon the shafts 21-25. Tapes 46 secured to the sheaves or pulleys 44 extend from such pulleys over the sheaves or pulleys 36 upon the shaft 35, and from thence about the sheaves or pulleys 36 upon the shaft 21 to 30 the sheaves 45 to which they are connected, the tapes 46 being adapted to be moved back, and forth from one to the other of the shafts 42 and 43, being wound upon one or the other of the set of sheaves 44-45. Each of 35 the shafts 37, 38, 42 and 43 is provided with a spiral spring 48 which resists turning of the shaft relative to the frame 10. Each of the springs 48 is so mounted as to have a tendency to turn its shaft in the direction to 40 wind the tapes 41-46 upon the sheaves mounted on that shaft,—that is to say, the springs upon the shafts 37-42 oppose the springs upon the shafts 38-43. The springs upon the shafts 37-42 are stronger, however, whereby the tapes 41-46 are adapted to be wound upon the sheaves 39-44 against the action of the springs upon the shafts 38-43 whenever the tapes are released for free movement. The shafts 38-43 are 45 adapted to be locked against rotation in the direction to unwind the tapes from the sheaves 40-45, this result being attained by the use of pawls 49 pivotally mounted upon the frame 10 and coöperating with notched 50 collars 50 upon the shafts 38-43. The shafts 38-43 are adapted to be rotated in the direction to wind the tapes 41-46 upon the sheaves 40-45, respectively, by means 55 of cords 51 wound upon drums 52, as is best shown in Fig. 3.

Before the roll 12 is entirely exhausted, a fresh roll 11 is inserted upon the spindle 13 to be substituted for the roll 12 when such roll is substantially exhausted. In due time 60 the belts 41 are to be wound upon the sheaves

or pulleys 40 by a pull upon the cord 51, this result being attained against the action of the spring 48 upon the shaft 37. The pawl 49 is then thrown into operative engagement with the notched collar 50 upon the shaft 38 70 for holding the tapes 41 against movement toward the left in Fig. 1. The end of the web of the roll 11 is then secured lightly in position upon the tapes 41 by any suitable means strong enough to resist the effective 75 pull of the springs 48 upon the shaft 37 but at the same time easily releasable at the proper moment. Such a connection may readily be effected by the use of pins or small paper stickers or pasters, as will be readily 80 understood. When the end of the web has been secured to the several tapes 41, the pawl 49 is turned out of engagement with the notched collar 50, whereupon the spring 48 on the shaft 37 exerts a constant pull upon 85 the web of the fresh roll, but not such a pull as is adapted to rotate the roll 11 for unwinding the web therefrom. When the web is substantially exhausted from the roll 12, a layer of adhesive material is applied to 90 the end of the web of the fresh roll, whereupon the parts are in readiness for the operation of splicing the end of the fresh web to the web running from the roll 12 whenever 95 by any suitable means the roll 11 is given a 100 rotation in clockwise direction in Fig. 1.

It will be understood that when the roll 11 becomes substantially exhausted a fresh roll is inserted upon the spindle 14, and the parts are prepared for the splicing operation in 105 the manner above described in connection with the fresh roll upon the spindle 13, the end of the web of the fresh roll in the lower position being secured to the tapes 46 rather than to the tapes 41.

The means which we have provided for 110 rotating a fresh roll in either of the two positions in the frame 10 and for bringing the rotation of the first roll very quickly to the same surface speed as that of the web 115 running from the roll in the other position, comprises a shaft 53 which is driven by any suitable mechanism from the press or other web machine. The shaft 53 is provided with the beveled gear 54 which meshes with a beveled gear 55 fixed upon the end of a 120 shaft 56 which is connected by means of gears 57-58 with sleeves 59 revolvably mounted upon a rock-shaft 60 extending across the frame below the shaft 56. The sleeves 59 have fixedly mounted thereon sheaves or pulleys 61 about which extend endless belts 62, the upper ends of which are supported by sheaves or pulleys 63 which are 125 revolvably mounted between arms 64-65. The arms 65 are swingingly mounted at their lower ends about the sleeves 59, while the arms 64 are fixedly connected at their lower ends with the rock-shaft 60. The belts 62 are thus adapted to be driven con- 130

tinuously through the shaft 56, the gears 57-58 and the sleeves 59, and the belts 62 are adapted to be swung about the axis of the rock-shaft 60 by reason of the fixed connection between the arms 64 and said rock-shaft. The rock-shaft 60 is adapted to be given a limited rotation in either direction by means of a segmental gear 66, fixed upon the end of said shaft, meshing with another segmental gear 67 revolubly mounted upon the frame 10 and provided with a handle or lever 68 for turning it.

The shaft 53 is provided at its lower end with another beveled gear 69 meshing with a beveled gear 70 mounted upon a shaft 71 which is connected by means of gears 72-73 with sleeves 74 revolubly mounted upon a shaft 75. The sleeves 74 are provided with sheaves 76 which support the upper ends of endless belts 77, the lower ends of which pass about sheaves 78 revolubly mounted between arms 79-80 depending from the rock shaft 75. The upper ends of the arms 80 are revolubly mounted about the sleeves 74, but the upper ends of the arms 79 are fixedly mounted upon the shaft 75, the belts being thus adapted to be swung about the shaft 75, while being free to be driven by the shaft 71. The shaft 75 is provided at its outer end with a segmental gear 81 which meshes with the gear 67.

The shaft 53 is driven constantly at such a speed as to cause the belts 62-77 to have the same surface speed as that of the web running to the press or other web machine. When a fresh roll in the upper position is to be substituted for the substantially exhausted roll in the lower position, when the parts have been all prepared for the change as above described, the lever 68 is given a sharp upward movement, bringing the belt 62 into contact with the periphery of the upper roll, serving to set such roll very quickly into rotation at the same surface speed as that of the web running from the lower roll. The spring 48 upon the shaft 37 serves to draw the tapes 41 toward the left in Fig. 1 as rotation of the roll 11 proceeds. It will be understood that in practice the distance between the shafts 33 and 24 will be such that by the time the end of the web of the fresh roll has been carried by the tapes 41 from its position adjacent to the shaft 33 into the bite of the rollers 22-23, the roll 11 will have assumed its full speed rotation at the desired surface speed. When the gummed end of the web of the fresh roll is brought into contact with the running web between rollers 22-23, it is pressed firmly against such web and thus fixedly secured thereto. As the end of the fresh web passes the roller 22, the means by which the end of the web is secured to the tapes 41 are released, by reason of the fact that the connection of the fresh web to the old web by means of the gum is

very much stronger than the connection of the fresh web to the tapes. When the end of the fresh web has passed beyond the rollers 22-23 and has thus been secured firmly to the running web, a blade 82 is given a downward movement about the shaft 83 upon which it is swingingly mounted for severing the old web. In the construction shown the shaft 83 of the severing blade 82 is swung by means of a head 84 which is adapted to be turned in either direction as desired by means of cords 85-86 attached to its opposite sides.

In the construction shown the tapes 41-46 are separated by a sufficient space between the rollers 22 and 23 so as to permit such tapes to be moved to the right in Fig. 1 without interfering with the movement of the running web at the same time toward the left in said figure.

As will be readily understood, when a fresh roll in the lower position is to be substituted for a substantially exhausted roll in the upper position, the lever 68 will be swung sharply downward, instead of upward as above described, for bringing the belts 77 into contact with the roll in the lower position for setting it into rotation at the desired speed.

That which we claim as our invention, and desire to secure by Letters Patent, is,—

1. The combination of a frame, means for revolubly supporting a web roll on said frame adjacent to a running web, means for rotating said web roll at a surface speed substantially equal to the speed of the running web, and intermittently operable means adapted to operate to automatically lead the end of the web from said web roll into contact with the running web when said roll is rotated.

2. The combination of a frame, means for revolubly supporting a web roll on said frame adjacent to a running web, means for rotating said web roll at a surface speed substantially equal to the speed of the running web, a tape to which the end of the web from said roll may be releasably secured, for leading said web into contact with the running web, and power operated means adapted when said roll is rotated to actuate said tape to carry the end of the web from said web roll into contact with the running web.

3. The combination of a frame, means for revolubly supporting a web roll on said frame adjacent to a running web, and reciprocating means adapted to lead the end of the web from the roll into contact with the running web when said roll is rotated.

4. The combination of a frame, means for revolubly supporting a web roll on said frame adjacent to a running web, means for rotating said web roll at a surface speed substantially equal to the speed of the run-

ning web, a tape to which the end of the web from said roll may be releasably secured, for leading said web into contact with the running web, and spring actuated means 5 adapted to actuate said tape to carry the end of the web from said web roll forward when said roll is rotated but not of sufficient effective strength to cause said roll to rotate.

5. The combination of a frame, means for 10 revolvably supporting a web roll on said frame adjacent to a running web, means for rotating said web roll at a surface speed substantially equal to the speed of the running web, a tape to which the end of the web 15 from said roll may be releasably secured for leading said web into contact with the running web, spring actuated means adapted to actuate said tape to carry the end of the web from said web roll forward when 20 said roll is rotated, and slightly weaker spring actuated means tending to draw said tape backward preparatory for an operative actuation thereof.

6. The combination of a frame means for 25 revolvably supporting a web roll on said frame adjacent to a running web, means for rotating said web roll at a surface speed substantially equal to the speed of the running web, a pair of coacting rollers between 30 which said running web passes, a tape to which the end of the web from said roll may be releasably secured, for leading said web into the bite of said rollers, and means adapted when said roll is rotated to actuate 35 said tape to carry the end of the web from said web roll into the bite of said rollers.

7. The combination of a frame, means for 40 revolvably supporting a web roll on said frame adjacent to a running web, means for rotating said web roll at a surface speed substantially equal to the speed of the running web, a pair of coacting endless belts between which said running web passes, a tape to which the end of the web from said 45 roll may be releasably secured, for leading said web into the bite of said endless belts, and means adapted when said roll is rotated to automatically actuate said tape to carry the end of the web from said web roll into 50 the bite of said belts.

8. The combination of a frame, means for 55 revolvably supporting a web roll on said frame adjacent to a running web, a reciprocating tape to which the end of the web from said roll is secured for leading said web into contact with the running web, and means adapted when said roll is rotated to actuate said tape to carry the end of the web from said roll forward.

60 9. The combination of a frame, means for 65 revolvably supporting a web roll on said frame adjacent to a running web, means for rotating said roll, and spring actuated means adapted to travel with and carry the end of the web from the roll into contact

with the running web when said roll is rotated.

10. The combination of a frame, means for revolvably supporting a web roll on said frame adjacent to a running web, means for 70 rotating said roll substantially at the same surface speed as that of the running web, and spring actuated reciprocating means adapted automatically to travel with and carry the end of the web from the roll into 75 contact with the running web when said roll is rotated.

11. The combination of a frame, means for revolvably supporting a web roll on said frame adjacent to a running web, a reciprocating 80 tape to which the end of the web from said roll may be releasably secured for leading said web into contact with the running web, means for rotating said roll substantially at the same surface speed as that of 85 the running web, and means adapted when said roll is rotated to actuate said tape to carry the web from said web roll forward.

12. The combination of a frame, means for revolvably supporting a web roll on said 90 frame adjacent to a running web, a reciprocating tape to which the end of the web from said roll may be releasably secured for leading 95 said web into contact with the running web, means for rotating said roll substantially at the same surface speed as that of the running web, means adapted when said roll is rotated to actuate said tape to carry the web from said web roll forward, and means for securing said two webs together 100 when they are brought into contact with each other.

13. The combination of a frame, means for revolvably supporting a web roll on said frame adjacent to a running web, a tape to 105 which the end of the web from said roll is releasably secured to lead said web into contact with the running web, yielding means adapted to give said tape an operative actuation for carrying the tape forward when 110 said roll is rotated, slightly weaker yielding means tending to draw said tape backward preparatory for an operative actuation, and other means for drawing said tape backward for connecting the end of the web 115 from the roll thereto.

14. The combination of a frame, means for revolvably supporting a web roll on said frame adjacent to a running web, a tape to 120 which the end of the web from said roll is releasably secured to lead said web into contact with the running web, yielding means adapted to give said tape an operative actuation for carrying the web forward when said roll is rotated, means for drawing said 125 tape backward against the action of said yielding means for connecting the end of the web from the roll thereto, and latch mechanism for holding the tape against forward movement.

15. The combination of a frame, means for revolvably supporting a web roll on said frame adjacent to a running web, a pair of coacting rollers between which said running web passes, a tape extending between said rollers to which the end of the web from said roll may be releasably secured for leading said web into the bite of said rollers, means adapted when said roll is rotated to 45
5
actuate said tape to carry the end of the web from said web roll into the bite of said rollers, and means for securing said two webs together as they pass between said rollers.
16. The combination of a framework, 10 means for revolvably supporting two web rolls upon said framework adjacent to each other, means for rotating a fresh roll in either position at substantially the same surface speed as that of the web running from 15
20 the other roll, and reciprocating means adapted to lead the end of the web from the fresh roll into contact with the running web when said roll is rotated.
17. The combination of a framework, 25 means for revolvably supporting two web rolls upon said framework adjacent to each other, means for rotating a fresh roll in either position at substantially the same surface speed as that of the web running from 30
35 the other roll, and yieldingly-actuated reciprocating means adapted to lead the end of the web from the fresh roll into contact with the running web when said roll is rotated.
18. The combination of a framework, 40 means for revolvably supporting two web rolls upon said framework adjacent to each other, means for rotating a fresh roll in either position at substantially the same surface speed as that of the web running from 45
50 the other roll, a tape to which the end of the web from a fresh roll in one position is secured for leading said web into contact with the running web, a second tape to which 55
60
65
70
75
80
85
the end of the web from a fresh roll in the other position is secured for leading such web into contact with the running web, and yielding means for each of said tapes adapted to give said tape an operative actuation for carrying the attached web forward when the fresh roll is rotated, said yielding means being of insufficient strength to cause said roll to rotate.
19. The combination of a framework, means for revolvably supporting two web rolls upon said framework adjacent to each other, means for rotating a fresh roll in either position at substantially the same surface speed as that of the web running from the other roll, yieldingly-actuated means adapted automatically to lead the end of the web from the fresh roll into contact with the running web when said roll is rotated, means for securing said two webs together when they are brought into contact with each other, and means for severing the old running web after the new web has been spliced thereto.
20. The combination of a framework, 70 means for revolvably supporting two web rolls upon said framework adjacent to each other, means for rotating a fresh roll in either position at substantially the same surface speed as that of the web running from the other roll, yieldingly-actuated means adapted automatically to lead the end of the 75 web from the fresh roll into contact with the running web when said roll is rotated, means for securing said two webs together 80
85
when they are brought into contact with each other, and a blade swingingly mounted between the paths of the webs from said rolls respectively adapted to be swung into engagement with the web from either roll for severing said web.

SAMUEL G. GOSS.
ERNEST JAMES SMITH.
